BUTTER DISH

Howard L. Forman, Belle Harbor, N. Y.

Application February 17, 1951, Serial No. 14,258

Term of patent 14 years

(Cl. D44—5)

To all whom it may concern:

Be it known that Howard L. Forman, a citizen of the United States, residing at Belle Harbor, in the county of Queens and State of New York, has invented a new, original, and ornamental Design for Butter Dish, of which the following is a specification, reference being had to the accompanying drawing, forming part thereof.

In the drawing

Fig. 1 is a top plan view of a butter dish, showing my new design;

Fig. 2 is an elevational view thereof, with parts cut away and parts in section;

Fig. 3 is a top plan view thereof, with the cover removed and part of the perforated support cut away.

The ornamentation partly completed in Figs. 1 and 3 is continued around the periphery outlined in dotted lines.

The dominant features reside in the butter

dish as shown and described excepting the knob drawn in broken lines.

I claim:

The ornamental design for a butter dish, as shown and described.

HOWARD L. FORMAN.
